UNITED STATES PATENT OFFICE

REINHOLD A. BARTHOLDI, OF DULUTH, MINNESOTA

DESIGN FOR A SHOW CASE OR SIMILAR ARTICLE

Application filed October 19, 1929. Serial No. 33,107. Term of patent 14 years.

To all whom it may concern:

Be it known that I, REINHOLD A. BARTHOLDI, a citizen of the United States, residing at Duluth, in the county of St. Louis and State of Minnesota, have invented a new, original, and ornamental Design for a Show Case or Similar Article, of which the following is a specification, reference being had to the accompanying drawing, forming part thereof,

The figure is a perspective view of a show case or similar article, showing my new design.

I claim:

The ornamental design for a show case or similar article as shown.

REINHOLD A. BARTHOLDI.
